PROTECTIVE SHIELD FOR FURNITURE

Orian A. Smith, Los Angeles, Calif.

Application April 9, 1938, Serial No. 201,125

4 Claims. (Cl. 45—22)

This invention relates to means for protecting furniture and the like from injury during shipment, storage and handling and relates more particularly to protective coverings or shields for furniture and like articles. A general object of this invention is to provide simple inexpensive and effective protective coverings or shields of the character referred to.

When upholstered furniture is to be shipped, stored or subjected to considerable handling it is usually necessary to protect the arms, back and other parts of the pieces of furniture against injury by heavy blows, friction, careless handling, dirt, etc.

Another object of this invention is to provide a simple one-piece protective covering element or shield that may be easily and quickly applied to the back, arms and other parts of a piece of furniture to protect the same against injury.

Another object of this invention is to provide a protective covering or shield of the character mentioned that is cut, shaped and pre-scored to be readily applied and to be easily shaped to conform to furniture parts of various sizes and configurations.

Another object of this invention is to provide furniture coverings or shields of the character mentioned that embody means or parts for facilitating their rapid yet secure attachment to the furniture articles.

Another object of this invention is to provide protective coverings or shields of the character referred to that may be supplied to the users in the form of compact flat sheets that are light in weight and readily shipped and handled.

Another object of this invention is to provide protective coverings or shields for furniture and the like that may be applied and removed without marking, soiling, defacing or otherwise injuring the furniture.

Another object of this invention is to provide a protective covering or shield that is adapted to fully enclose and cover the ends, top and corners of the back, arm or a similar part of an article of furniture to adequately protect the same against injury.

A further object of this invention is to provide protective coverings or shields for furniture that are simple and inexpensive to manufacture.

Other objects and features of my invention will be better and more fully understood from the following detailed description of typical preferred applications of the invention, throughout

which description reference is made to the accompanying drawings in which:

Fig. 1 is a front perspective view of a typical upholstered chair illustrating the protective shields of the invention arranged thereon. Fig. 2 is a fragmentary front view of a typical upholstered davenport with several shields of the invention thereon. Fig. 3 is an end view of the chair shown in Fig. 1. Fig. 4 is an enlarged fragmentary end view of the chair with a portion broken away to illustrate the manner in which the cushion retaining band is held in the chair structure. Fig. 5 is a fragmentary end view of another article of upholstered furniture showing one of the shields of the invention arranged thereon and Fig. 6 is a plan view of one of the protective coverings or shields in its normal or original state.

The furniture coverings or shields of the present invention may be employed to cover and protect articles of furniture, etc., of various natures and may be varied somewhat to adapt them for use on different articles. In the following detailed description I will describe a typical preferred form of the invention as employed on upholstered chairs and an upholstered davenport. It is to be understood that the invention is not to be construed as limited or restricted to the specific form or applications of the invention about to be described but that it is to be taken as including any features or modifications that may fall within the scope of the claims.

It is believed that the manner of applying and using the coverings or shields of the invention will be better understood following a detailed description of one of the shields in its original condition and I will proceed with a description of the typical protective covering or shield of the invention illustrated in Fig. 6 of the drawings.

The improved covering element or protective shield of the invention illustrated in Fig. 6 of the drawings comprises, generally, a sheet-like body 10 having series of cuts or slots 11 and series of lines of scoring 12 and 13 to condition it for shaping and folding, and cuts 14 providing the body 10 with attaching tabs or straps 15.

The covering body or shield body 10 is in the nature of a square or rectangular sheet of fibrous material such as cardboard, paper, felt, fabric, or the like. In practice it has been found desirable to form the body 10 of double-faced corrugated paper board or fibre board. The material of which the body 10 is formed is of sufficient strength to resist the blows and friction to which it may be subjected and yet it is sufficiently pli-

able to be shaped, bent and folded without cracking. As illustrated in the drawings the body 10 is substantially square in plan view, it being understood that it may be elongate or rectangular as conditions may require. The margins or edges 16 of the body 10 are preferably straight and at right angles to one another.

The cuts or slots 11 are provided in the body 10 to facilitate the shaping or forming of the body 10 to extend over corners, edges, etc., of furniture parts and to facilitate the attachment of the body 10 to the furniture. There are preferably two series of slots 11 provided in the body 10, the slots entering the body from two opposite edges 16. The cuts or slots 11 of a series are parallel and are at right angles to the adjacent body edge 16. In the typical form of the invention illustrated in Fig. 6 there are eight slots 11 in each of two opposite edge portions of the body 10, each series having four slots spaced at each side of a central or medial plane of the body. The spacing of the slots 11 in a series may be varied to suit the conditions of use. In Fig. 6 of the drawings I have illustrated a typical preferred arrangement of slots 11 in which the slots 11 in adjacent relation to the above-mentioned medial plane are in closer relation than the slots which are more remote from the said medial plane. The cuts or slots 11 at the opposite edges 30 or side portions of the body 10 are in longitudinal alignment. In making or providing the slots 11 it is preferred to remove or cut out strips of the body material so that the slots 11 are open as illustrated in the drawings. The slots 11 just described provide two opposite edge portions of the body 10 with pluralities of adjacent elongate tabs or flaps 17 of varying or graduated width. It will be observed that the portions of the body 10 between the outermost slots 11 and the adjacent parallel body edge 16 constitute rather wide corner tabs or flaps 18.

The lines 12 of scoring extend between and connect the longitudinally aligned slots 11 in the two opposite edge portions of the body 10. The lines 12 extend completely across the body 10 from the inner ends of the slots 11 of one series to the inner ends of the slots 11 of the other series of slots. The lines 12 may be formed or provided in any manner that facilitates the bending or folding of the body 10 at these lines. The lines 12 of scoring are such that the body 10 may be folded or bent along them without cracking or tearing. In accordance with the invention the shield body 10 is provided with the lines 13 of bending or scoring extending in right angled relation to the above described lines 12. There are two sets of lines 13. One line 13 of each set intersects the lines 12 at the inner ends of the slots 11 in an edge portion of the body 10 and the other lines 13 of the sets intersect or cross the slots 11. This relationship between the lines 12 and 13 of folding or scoring is clearly illustrated in Fig. 6 of the drawings. One set comprises two substantially parallel lines 13 and the other set preferably comprises three substantially parallel lines 13. It will be observed that the other lines 13 of folding extend in parallel relation to the adjacent body edges 16 and traverse or extend across the above-mentioned tabs or flaps 17 and corner body portions 18. These outer lines 13 of scoring allow the flaps 17 and the corner portions 18 to be easily folded or bent as will be subsequently described. The lines 13 of one set may be in closer relation than the lines 13 of the other set or pair. In the drawings the several lines of

folding or scoring provided on the body 10 are shown as broken lines to better distinguish them from the cuts or slots 11 and 14.

The cuts or slots 14 are located to provide the body 10 with securing or attaching straps 15. There are preferably two slots 14 entering the body 10 from adjacent two diagonally related corners of the body. The slots 14 are in parallel relation to the slots 11 and therefore are substantially parallel to the adjacent body edges 16 so that the portions of the body 10 between the slots 14 and the adjacent edges 16 are elongate and of substantially uniform width. These elongate portions of the body 10 constitute the securing or attaching strips or straps 15. In accordance with the invention the cuts or slots 14 are of substantial length so that the straps 15 are sufficiently long to be employed to secure the shield or body 10 to furniture parts of substantial size. For this reason the cuts or slots 14 may be considerably longer than the slots 11. It is preferred to terminate the lines 13 of folding or scoring at the cuts or slots 14 so that the lines do not cross the straps 15 to weaken the straps or render the straps excessively flexible.

In accordance with the invention the securing or attaching straps 15 are adapted to be extended laterally or transversely from the adjacent body edges 16 and it is preferred to provide lines 19 of folding at the inner ends of the straps. The lines 19 of folding extend from the adjacent body edges 16 to the inner ends of the slots 14 and are pitched or arranged at an angle to the said adjacent edges 16 so that the straps 15 may be bent or folded out to be at substantially right angles to the said edges 16. It is to be observed that the securing or attaching straps 15 are integral parts of the simple sheet-like body 10. The parts are related and formed so that the attaching straps 15 are in approximate longitudinal alignment when they are both extended and preferably lie in a medial plane of the body 10.

The shield body 10 described above may be easily and inexpensively formed from suitable sheet material. The body 10 may be quickly cut to the desired size and inexpensively provided with the several cuts or slots and the lines of scoring. The shield body 10 is an integral sheet-like part that may be conveniently handled and that may be readily stacked with other shields of the same kind for packaging, shipping, etc.

Figs. 1, 3 and 4 of the drawings illustrate the manner of employing several protective shields of the invention on a typical overstuffed or upholstered chair. The chair illustrated in the drawings includes arms 20, a back 21 and a seat cushion 22 and, of course, includes the usual frame, bottom, spring structures, etc. A shield body 10 of the character described above is arranged or draped over each chair arm 20 to have its lines 12 and slots 11 extend longitudinally thereof. The shield bodies 10 are positioned so that the lines 12 of folding or scoring occur at the upper rounded portions of the arms 20 and so that the flaps 17 at their forward ends protrude from the front ends of the arms. The lines 12 allow the bodies 10 to be easily bent or formed to the shape of the curved arms 20 and when the bodies 10 have been shaped or bent along the lines 12 they fully conform to the upper portions of the chair arms. From an inspection of Fig. 1 of the drawings it will be seen that large edge portions 24 of the bodies 10, located between the outermost lines 12 and the parallel body edges 16, cover and protect large parts of the in-

ner and outer sides of the chair arms 20. The flaps 17 at the forward ends of the shields are bent downwardly along the most convenient line 13 to lie flat against the forward faces of the chair arms 20. The flaps 17 at the forward ends 5 of the chair arms 20 are preferably arranged in overlapping relation and it may be preferred to arrange the central flaps outermost to better retain the other tabs in place. When the flaps 10 have been folded and lapped together adhesive tapes 25 are arranged across the outer flaps and are arranged to extend onto the bodies 10 to opposite sides of the chair arms 20. The adhesive tapes 25 serve to dependably retain the tabs or 15 flaps 17 in position. It is to be noted that the flaps 17 effectively cover the upper forward face portions of the chair arms 20 and that the shields fully protect the forward upper corners of the arms. 20 The largest corner portions 18 of the bodies 10 occurring at the forward ends of the arms 29 are made to lie against the forward faces of the arms 20 by bending the bodies along the most convenient lines 13. Fig. 1 of the drawings illustrates the manner in which these corner portions 18 of the bodies 10 cover and protect substantial portions of the front faces of the chair arms 29. The flaps 17 at the rear ends of the bodies 10 may be flared or folded out along the most convenient lines 13 to conform to or lie against the front face of the chair back 21 and the side faces of the chair back. The rear corner portions 18 of the bodies 10 may be made to lie against the front face of the chair back 21 and against the 35 rear face of the chair back. The manner in which the flaps 17 are held against the chair back 21 will be hereinafter described. 30 The straps 15 of the shield bodies 10, that are arranged on the chair arms 20, may be employed to dependably retain the shields on the chair. The straps 15 occurring at the outer sides of the chair arms 20 are made to extend downwardly across the outer sides of the arms by folding the shields along the lines 19. The lower parts of 40 these outer straps 15 are turned in at the under side of the chair and these turned-in parts are tacked or otherwise secured to the chair frame. The straps 15 that occur at the inner sides of the chair arms 20 are extended or projected to extend downwardly on the inner faces of the 45 arms and their lower parts are then turned inwardly to lie against the chair bottom. The seat cushion 22 rests down against these in-turned parts of the straps 15 to retain the straps in place. The cushion 22 is retained in the chair in 50 the manner to be hereinafter described. 55 It will be noted that the straps 15 at the opposite sides of the bodies 10 hold the shields down on the chair arms 20. The lines of bending or scoring 12 allow the bodies 10 to be shaped to conform to the particular curvature of the arms 28. For example, where the arms 20 have an outward or lateral curvature, as illustrated in the drawings, the lines 12 allow the bodies to be 60 trained over the laterally curved arms to fully protect their upper portions. The lapped or intermeshing flaps 17 held together at the front ends of the arms 20 assist the straps 15 in holding the bodies 10 on the arms. It will be observed 65 that the bodies 10 are dependably secured to or retained on the chair arms without employing fastening devices that mar or enter the fabric of the upholstered chair. 70 A protective device or shield of the invention 75 is shown arranged in place on the back 21 of the

chair. The body 10 or the shield is laid on the top of the chair back 21 and bent along its lines 12 to engage over the top and have its major side portions 24 lie against the front and rear faces of the back. The body 10 is bent along the desired or convenient lines 13 to have its flaps 17 engage down over the opposite sides of the chair back 21. The spaced adjacent lines 13 of scoring allow the flaps 17 to be trained over the rounded upper corners of the chair back 21. If 10 desired or found practical the large corner flaps or corner portions 18 may be engaged against the opposite sides of the chair back 21 to cover and protect substantial portions of the same. The flaps 17 and, if necessary, the corner portions 18 15 may be retained in place by adhesive tapes 27. The tapes 27 may continue across the lapped or adjacent flaps 17 to have their end portions at the front and back parts of the shield body 10. As clearly illustrated in Fig. 1 of the drawings 20 the front major portion of the body 10, trained over the chair back 21, overlaps or engages over certain of the rear flaps 17 of the shield bodies 10 arranged on the chair arms 20. This engagement assists in retaining the shields or bodies 25 10 on the chair arms 20. The strap 15 on the rear portion of the shield body 10 is trained down across the rear face of the chair back 21 and its lower portion is turned in under the frame of the chair. Thus turned-in lower portion of the strap 30 15 may be secured to the chair frame by tacks, or the like. The strap 15 on the forward portion of the body 10 is trained down across the front face of the chair back 21 and its lower portion is bent forwardly to be under the seat cushion 22. 35 The cushion 22 thus serves to hold the forward strap 15 in place and assists in securing the back-protecting shield to the chair. 40 The invention arranged on the chair back 21, as just described, fully covers the top of the back 21 and the upper corner portions of the back and extends down over substantial parts of the front and rear faces of the back. Thus the shield adequately protects the various edges, corners, etc., of the 45 back 21 and substantial face portions of the back. 50 The invention provides novel means for retaining the seat cushion 22 in place, so that the cushion in turn holds the straps 15 against displacement. The cushion 22 is retained in place 55 by a strip or band 28 of tape, canvas, burlap, or other suitable fabric. The band 28 is arranged across the upper face of the cushion 22 and its rear portion is trained down between the cushion 22 and the chair back 21. The rear end part 55 of the band 28 is rolled about a body of batting 29, or the like, and this rolled portion of the band is introduced between the bottom spring structure 30 and the back spring structure 31 of the chair. As best illustrated in Fig. 4 of the 60 drawings the spring structure 30 is covered by fabric 32 and the spring structure 31 is covered by fabric 33. Prior to the arrangement of the cushion 22 in the chair the rolled end portion of the band 28 enclosing the batting 29 is pushed 65 down between the engaging parts of the fabric 32 and 33. In arranging the lower part of the band 28 in place the spring structures 30 and 31 yield or part and when the workman applying the band removes his hand the spring structures 70 75 are returned to their original positions so that the rolled-up end of the band 28 is gripped or held between the spring structures. The cushion 22 is then arranged in place and the band 28 is trained across its upper side and down across

the front of the chair. The forward end portion of the band 28 is turned under the frame of the chair and may be tacked or otherwise secured to the chair frame. It is believed that it will be apparent how the band 28 arranged as just described holds the seat cushion 22 in place and how the cushion 22 in turn holds the adjacent or inner shield straps 15 down to assist in retaining their respective shield bodies 10 on the chair.

In Fig. 2 of the drawings I have illustrated the guards or shields of the invention arranged on a portion of a typical overstuffed or upholstered davenport. The arms of the davenport may be provided or covered with the shields in the same manner as the arms 20 of the chair illustrated in Figs. 1, 3 and 4 of the drawings, and the seat cushions 30 of the davenport may be held in place by the bands 28 in the same manner as the chair cushion 22.

The bodies 10 of two or more of the shields may be arranged or draped over the back 31 of the davenport. The flaps 17 and, if desired, the corner portions 18 of the shields occurring at the ends of the back 21 may be bent down over the said ends and secured in place by adhesive tapes 32 to protect the ends of the back 31. The large major portions 24 of the shield bodies 10 extend down over substantial portions of the front and rear faces of the davenport back 31. The straps 15 at the rear face of the back 31 may be trained down across the back and tacked to the davenport frame. The straps 15 at the forward face of the back 31 may be trained down across the back and turned under or forwardly to be held down by the cushions 30.

The adjacent ends of the aligned shield bodies 10 on the davenport back 31 may be arranged in overlapping relation and, if desired, their flaps 17 may be arranged in intermeshing relation. One or more lengths of adhesive tape 33 may be arranged across the overlapping or intermeshing flaps 17 to hold them in place and to connect the adjacent shields. If desired or found necessary slots or cuts 34 may be formed in the large corner portions 18 at the adjoining ends of the shield bodies 10 to facilitate the overlapping or intermeshing of the shield parts. The shield bodies 10 are dependably held on the davenport back 31 by their straps 15 and by the engagement of their flaps 17 about the opposite end portions of the back 31.

Fig. 5 of the drawings illustrates a shield of the invention arranged on the arm 35 of a davenport or chair to protect the same. The arm 35 has a concave upper side or top. The shield body 10 may be arranged on the arm 35 in the same manner as in the previously described applications of the invention. In order to adapt the shield body to the arm 35 one or more cuts 38 may be provided in the body 10 in transverse relation to the bend lines or lines 12 of scoring. These cuts 38 may, if necessary, intersect the lines 12 and allow the depending portions of the body 10 to be extended longitudinally and shaped to the arm 35 without distortion. The straps 15 may be employed to hold the shield body 10 on the arm 38 and the flaps 17 and the corner portion 18 may be arranged across the front of the arm 35, all described above.

It is believed that it will be understood how the furniture shields of the invention may be

employed on various articles of furniture. The shields are constructed so that they may be easily and quickly arranged in place on a part of furniture of practically any configuration. The shields may be applied to and secured to the furniture without in any way injuring or defacing the furniture. In a like manner the shields may be easily and quickly removed from the furniture. To remove a shield its straps 15 are cut or pulled loose and this frees the shield for easy removal from the article of furniture. The shields of the invention may be shaped or trained to extend about the ends, edges, and corners of the furniture articles to adequately protect the same against blows, dirt, rubbing, etc. The shields are simple and inexpensive to manufacture and are convenient to handle.

Having described only a typical preferred form and typical preferred applications of my invention, I do not wish to be limited or restricted to the specific details herein set forth, but wish to reserve to myself any variations or modifications that may appear to those skilled in the art or fall within the scope of the following claims.

Having described my invention, I claim:

1. A shield for protecting an article of furniture comprising a sheet-like body having a series of fold lines whereby it may be draped over said article and having slits in substantially parallel relation to the said lines and in adjacent relation to opposite edges of the body and extending in opposite directions to terminate at the other edges of the body adjacent diagonally related corners of the body and defining straps laterally projectable from said other edges for securing the body to the article.

2. A shield for protecting an article of furniture comprising a sheet-like body having a series of fold lines whereby it may be draped over said article and having slots substantially parallel with the said lines and extending in opposite directions to opposite ends of the body in spaced adjacent relation to other ends of the body to define straps capable of lateral projection from said other ends for securing the body to the said article.

3. A shield for protecting an article of furniture comprising a sheet-like body having a series of fold lines whereby it may be draped over said article, having series of slots extending inwardly from opposite ends of the body to define flaps for engagement over ends of the said article, and having cuts extending inwardly from said ends of the body in adjacent relation to the other ends of the body defining straps capable of lateral extension from the said other ends to secure the body to the article.

4. A shield for protecting an article of furniture comprising a sheet-like body having a series of fold lines whereby it may be draped over said article, having series of slots extending inwardly from opposite ends of the body to define flaps for engagement over ends of the said article, having bend lines transverse of said slots to facilitate the engagement of the flaps over the ends of the article, and having cuts extending inwardly from said ends of the body in adjacent relation to the other ends of the body defining straps capable of lateral extension from the said other ends to secure the body to the article.
